UNITED STATES PATENT OFFICE

DAVID GREENWALD, OF NEW YORK, N. Y.

AIRPLANE HANGAR DOOR

Application filed September 22, 1930. Serial No. 483,535.

This invention relates to doors for hangars or manufacturing buildings for airplanes, zeppelins, balloons or similar vehicles. In such structures the entrances are required to be very large, wide, high, and unobstructed, and heretofore the doors utilized for opening and closing such entrances were inefficient and embodied many well known disadvantages.

10 The principal object of the invention is to provide doors for the above mentioned purpose, which may be conveniently and economically installed, wherewith entrances of any required width and height may be readily, rapidly, and conveniently closed and opened without any obstruction, which will efficiently resist any wind pressure or dislocation, and which will be strong, durable, efficient, and improved.

20 Other objects and advantages will hereinafter appear.

In the accompanying drawings,—

Fig. 1 shows an elevation of a portion of a building equipped with the doors constituting the invention, the remainder of the building and improvements not being shown for convenience of illustration.

Fig. 2 is a transverse-sectional side elevation of the doors shown in Fig. 1.

30 Fig. 3 is a view similar to that shown in Fig. 2, but showing the doors in opened state.

Fig. 4 is a plan view, in an enlarged scale, showing a detail of the invention.

35 At each side of the large opening 1 of the building 2 is provided a vertical guiding-way 3, and between said guiding-ways is located a series of mullions 4. Between each of said guiding-ways and its adjoining mullion and between each adjoining pair of said mullions is located a door-section 5, all of which sections are intended to normally close the lower areaway of the opening 1, as shown in Figs. 1, 2. The door-sections 5 are secured to the mullions 4, while the ends of the door-sections lodging in the guiding-ways 3 are vertically slideable therein. In the upper areaway of the opening 1 is located a series of door-sections 6, which are similar to the door-sections 5 and are intended to normally

close the upper areaway in a similar manner. The door-sections 6 are slideable in channels 7, Fig. 4, of their respective mullions, while the ends of the door-sections 6 lodging in the guiding-ways 3 are vertically slideable therein. The door-sections 6 are normally maintained in elevated state to close the upper areaway of opening 1, as shown in Figs. 1, 2, by means of hangers 8 thereof resting upon brackets 9 secured to the building. Each of the mullions 4 is vertically slideable, from a lowermost position shown in Figs. 1, 2 to an elevated position shown in Fig. 3, in guiding-ways 10 secured to the building-frame 2, in the manner shown in Fig. 4, and when the mullions are in lowered position their terminals 11 rest within cavities 12 formed in boxes 13 sunk in the floor 14 of the building. To each door-section 5 are secured several cables 15, each of which is carried around a pulley 16 running in brackets 17 secured to the building-frame, and from said pulley the cable extends to a sheave 18 to which it is secured and wound around. The sheaves 18 are in turn keyed upon a shaft 19 which is rotatable in bearings, not shown, mounted in the side-walls 20 of the building 2. At each end of shaft 19 is keyed a drum 21 around which is wound a cable 22 having to its terminal secured a counterweight 23, for counterbalancing the door-sections 5, 6 and vertically slideable mullions 4. About the shaft 19 and near each drum 21 is mounted a hoisting device 24 joined to a bracket 25 secured to the building-frame, which device is operable by the usual hoisting chain 26. Upon operation of either or both of the hoisting chains 26, the shaft 19 is rotated and the drums 18 are wound up to simultaneously elevate all of the counterbalanced door-sections 5 and the mullions 4 to which they are secured, from the position shown in Figs. 1, 2 to that shown in Fig. 3. In the ascendency of the door-sections 5, projections 27 thereof engage the door-sections 6 and elevate the latter to the position shown in Fig. 3, whereby the entire areaway of the large opening 1 of the building is cleared of all doors and mullions and rendered suitable for efficient entrance

and egress of airships. Upon the doors 5, 6 reaching their full ascendancy, projections 28 secured to the bottoms of the doors 6 strike the brackets 9 and thereby limit the upward movement, as shown in Fig. 3. When it is desired to close the opening 1 of the building, the same is accomplished by merely operating the hoisting chain 26 backwardly. In some situations the mullions 4 may project above the roof 29 of the building when fully elevated, as illustrated in Fig. 3, and in such cases a hinged shutter 30 may be provided above each mullion in the roof 29, which shutter will automatically open up by the raising of the mullion and will close up by its gravity upon lowering of the mullion, as shown in Fig. 1, for proper protection of the building.

It will be evident in this invention that the door-sections 5, 6 and movable mullions 4 may be indefinitely multiplied to provide for any width and height of opening of the building, to completely open and clear the latter of any obstruction for efficient use of the building, and that the retention of the mullions in the guiding-ways 10 and ground boxes 13 will efficiently maintain the door closure against any wind pressure or other dislocation.

Variations may be resorted to within the scope of the invention, and portions of the improvements may be used without others.

Having thus described my invention, I claim:

1. A hangar closure comprising a plurality of vertical mullions adapted to slide vertically, vertical guiding means for said mullions, a plurality of door sections between each adjoining pair of said mullions being arranged at various elevations to close the area between said pair of mullions, the lowermost of said sections being secured to said mullions, the uppermost of said sections being in suspension, means to elevate said lowermost door-sections and mullions, and said lowermost sections raising said remaining sections therewith when ascending.

2. A hangar closure comprising a plurality of vertical mullions adapted to slide vertically, vertical guiding means for said mullions, a plurality of door sections between each adjoining pair of said mullions being arranged at various elevations to close the area between said pair of mullions, the lowermost of said sections being secured to said mullions, the uppermost of said sections being in suspension, means to elevate said lowermost door-sections and mullions, said lowermost sections raising said remaining sections therewith when ascending, and means at the ground for engaging each of said mullions upon its descent.

3. A hangar closure comprising a vertical mullion adapted to slide vertically, a plurality of door sections adjacent each side of

said mullion being arranged at various elevations to close the areas about said mullion, the lowermost of said sections adapted to be elevated together with said mullion, and said remaining sections being elevated with the elevation of said lowermost sections and mullion.

4. A hangar closure comprising a vertical mullion adapted to slide vertically, a plurality of door sections adjacent each side of said mullion being arranged at various elevations to close the areas about said mullion, the lowermost of said sections adapted to be elevated together with said mullion, said remaining sections being elevated with the elevation of said lowermost sections and mullion, and means at the ground engaging said mullion upon its descent.

5. A hangar closure comprising a plurality of vertical mullions adapted to slide vertically, guiding means for said mullions, a plurality of door sections between each adjoining pair of said mullions being arranged at various elevations to close the area between said pair of mullions, the lowermost of said sections adapted to be elevated together with said mullions, and the uppermost of said sections being slidable in said mullions and adapted to be elevated with the elevation of said mullions and lowermost sections.

6. A hangar closure comprising a plurality of vertical mullions adapted to slide vertically, guiding means for said mullions, a plurality of door sections between each adjoining pair of said mullions being arranged at various elevations to close the area between said pair of mullions, the lowermost of said sections adapted to be elevated together with said mullions, the uppermost of said sections being slidable in said mullions and adapted to be elevated with the elevation of said mullions and lowermost sections, and means at the ground for engaging each of said mullions upon its descent.

Signed at the city of New York, in the county of New York, and State of New York, this 20th day of September, A. D. 1930.

DAVID GREENWALD.
